(57) **CLAIM**

We claim the ornamental design for a building ridge, as shown and described.

DESCRIPTION

FIG. 1 is a front perspective view of the claimed building ridge, showing our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front view thereof; and,

FIG. 7 is a rear view thereof.
